[57] CLAIM

An ornamental design for an electrical insulator having sheds, as shown and described.

DESCRIPTION

FIG. 1 is a perspective view of the insulator device having sheds;

FIG. 2 is a side elevational view thereof;

FIG. 3 is an end elevational view thereof as seen from the left hand side of FIG. 2;

FIG. 4 is an end elevational view as seen from the right hand side of FIG. 2; and

FIG. 5 is a side elevational view similar to FIG. 2 with the device having been rotated through 90°.
